CLAIM

The ornamental design for an introducer handle for medical cannula, as shown and described.

DESCRIPTION

FIG. 1 is a top plan view of an introducer handle for medical cannula showing my new design, the bottom plan view being a mirror image thereto;

FIG. 2 is a front elevational view thereof, the rear elevational view being a mirror image thereto;

FIG. 3 is a left side elevational view thereof;

FIG. 4 is a right side elevational view thereof;

FIG. 5 is a cross-sectional view thereof, taken along the line 5—5 of FIG. 2; and,

FIG. 6 is a cross-sectional view thereof, taken along the line 6—6 of FIG. 2.

The broken line showing of the introducer in FIGS. 1 and 2 is for illustrative purposes only and forms no part of the claimed design.
